US00D715265S

(12) **United States Design Patent**
Kuramoto

(10) **Patent No.:** **US D715,265 S**
(45) **Date of Patent:** **** Oct. 14, 2014**

(54) **DIGITAL AUDIO PLAYER WITH A WIRELESS CONNECTION AND MIXING FUNCTION**

(71) Applicant: **Pioneer Corporation**, Kawasaki (JP)

(72) Inventor: **Takahiro Kuramoto**, Kanagawa (JP)

(73) Assignee: **Pioneer Corporation**, Kawasaki-shi, Kanagawa (JP)

(**) Term: **14 Years**

(21) Appl. No.: **29/444,932**

(22) Filed: **Feb. 6, 2013**

(30) **Foreign Application Priority Data**

Aug. 23, 2012 (JP) 2012-020155
